MINE PUMP

Joseph F. Joy, Claremont, N. H., assignor to Sullivan Machinery Company, a corporation of Massachusetts

Application December 22, 1936, Serial No. 117,177

8 Claims. (Cl. 103—150)

This invention relates to pumps, and more particularly, but not exclusively, has reference to improvements in a mine gathering pump of the multi-chamber, diaphragm type.

An object of this invention is to provide an improved pump of the multi-chamber, diaphragm type. Another object is to provide an improved pump wherein motor actuated diaphragms are employed for creating a suction in the chambers of the pump and for forcing the fluid from the pump chambers. Still another object is to provide an improved pump of the above named type that will be simple in construction, tending to reduce the number of parts, and reliable in operation. Still a further object is to provide an improved pump especially adapted for mine use, of low height, with simple and somewhat protected piping, providing substantially continuous discharge of fluid, and smooth-running. Other and further objects and advantages of the present invention will be apparent from the following description, reference being had to the accompanying drawings, wherein a preferred embodiment of one form of the invention is clearly shown.

In these drawings,—

Fig. 1 is a plan view of the illustrative form of the improved pump.

Fig. 2 is a side elevational view of the pump shown in Fig. 1.

Fig. 3 is a horizontal sectional view taken substantially on line 3—3 of Fig. 4.

Fig. 4 is an enlarged cross sectional view taken substantially on line 4—4 of Fig. 1.

Fig. 5 is an enlarged view in longitudinal section taken substantially on line 5—5 of Fig. 1.

In this illustrative embodiment of the invention there is shown a multi-chamber, diaphragm pump of the mine gathering type comprising a base 1 adapted to rest upon any suitable support or directly upon the mine bottom, and a pedestal frame 2 providing a gear casing supported on the base and in turn supporting from one wall thereof a horizontal motor 3. The motor power shaft 4 is suitably journaled at its opposite ends—45 at one end within a bearing 5 supported within the gear casing, while a reduced end thereof projects beyond said bearing within the gear casing and is splined by a coupling 6 to an alined transmission shaft 7. The shaft 7 is suitably journaled within bearings 8 and 9 supported within the gear casing and has formed thereon intermediate its ends and between the bearings, a worm 10 meshing with a worm wheel 11. This worm wheel is keyed to a horizontal shaft 12, this shaft extending 50 at right angles to the shaft 7 transversely of

the gear casing, herein above shaft 7, and suitably journaled in said casing within bearings 13, 13 preferably arranged within detachable bearing supports 14, 14 secured by screws 15 to the pedestal frame 2. The gear casing contains an oil bath in which the worm gears run, and the splashing of lubricant by the worm gears will lubricate the bearings 13, 13. Suitable packings 16, 16 surrounding the ends of the shaft preclude any leakage of lubricant from the gear casing past the bearings 13. In this illustrative construction, the ends of the shaft 12 are formed with eccentrically disposed crank pins 17, 17, herein arranged with respect to each other on the shaft 180° apart. Supported by the pins 17 are bearings 18 on which are mounted the hubs 19 of plunger-like members 20, each of which members has a circular bottom portion 21. As shown, the crank pins 17 and plunger-like members 20 are arranged exteriorly of the gear casing 20 at the opposite sides of the latter.

The base has formed therein parallel pump chambers 22, 22, one on each side of the base, and flexible annular diaphragms 23 are clamped at their outer peripheries to the base around the tops of the pump chambers, and at their inner peripheries to the bottom portions 21 of the plunger-like members. Each diaphragm is clamped at its outer periphery between a flange 24 formed integral with the base and a clamping ring 25 secured to the base flange by screws 26. The diaphragms are clamped near their inner peripheries between the circular portion 21 on the actuating member 20 and a clamping ring 27 secured to the member 21 by screws 28. It will thus be seen that the diaphragms provide partially flexible upper walls for the pump chambers. As shown in Figs. 1 and 2, an intake pipe 30 is connected through branched pipe connections 31 and 32 to the intake ports of the pump chambers, and the pump chamber discharge ports are connected through branched pipes 33 and 34 to a discharge pipe 35. The pipes 31 and 32 contain conventional intake check valves 36, 36, while the discharge pipes 33, 34 are provided with conventional discharge check valves 37, 37. The base is suitably stiffened and made stronger by ribs 38 extending between the pump chambers, and ribs 39, traversed by suitable flow openings 40, extend transversely of the pump chambers, these latter ribs being so reduced in height at their tops that they are not contacted either by diaphragms or plunger-like member bottoms.

The operation of the improved pump is as follows: When the motor 3 is operated, thus rotating

the motor shaft 4, the worm 10 will drive the worm wheel 11 and transverse shaft 12. Rotation of the shaft 12 will effect actuation of the crank pins 17, 17, which will reciprocate and slightly 5 oscillate the plunger-like members 20. As these plunger-like members 20 are reciprocated, the diaphragms 23, 23 will be flexed upwardly and downwardly in alternation. Upon the upward strokes of the plunger-like members, a suction 10 will be created in the pump chambers whereby fluid will flow from the source of supply through inlet pipe 30 and branched pipes 31 and 32 past the intake valves 36 into the pump chambers, during which time the discharge valves 37 are 15 automatically closed. On the downward strokes of the plunger-like members, the pressure within the pump chambers will open the discharge valves 37, and the intake valves 36 will be automatically closed. The fluid flowing through the discharge 20 valves will pass through the discharge pipes 33, 34 and the discharge pipe 35, which may be connected to deliver at any desired point. The pumping operation will continue as long as the motor 3 is operated and material to be pumped is 25 available. The gearing within the gear casing will be sufficiently lubricated, inasmuch as the worm and worm wheel are running continuously in oil, and the splashing of lubricant by the worm gearing will lubricate the shaft bearings 30 13. The plunger-like members of the pump for actuating the diaphragms flex the latter upwardly and downwardly in alternation, so that when one pump chamber is receiving fluid through the intake pipe, the other chamber is discharging 35 fluid through the discharge pipe.

As a result of this invention, it will be noted that an improved mine gathering pump of the diaphragm type is provided which is extremely simple and rugged in design, well adapted to 40 meet the severe demands of service. It will further be noted that by the improved arrangement of parts, the pump is well balanced and extremely compact. The pump is self-contained, strong and rigid in construction, and the motor is supported above the mine bottom and may be made 45 waterproof very readily. Other uses and advantages of the improved pump will be clearly apparent to those skilled in the art.

While there is in this application specifically 50 described one form which the invention may assume in practice, it will be understood that this form of the same is shown for purposes of illustration and that the invention may be modified and embodied in various other forms without departing from its spirit or the scope of the appended 55 claims.

What I claim as new and desire to secure by Letters Patent is:

1. A pump comprising, in combination, a base 60 on the bottom of which the pump is adapted to be supported and having a pump chamber formed therein, a motor supported by said base with its bottom disposed above the bottom of said base and having its power shaft horizontally disposed 65 in horizontal planes above said pump chamber, a flexible diaphragm in said chamber for creating a suction in said chamber and for forcing the fluid from said chamber, driving connections between said motor power shaft and said diaphragm 70 for flexing the latter, and inlet and discharge pipe connections extending along the sides of the base in horizontal planes near the bottom of the motor and in horizontal planes in adjacency to and above the bottom of said base, 75 said pipe connections communicating with said

pump chamber and certain of said pipe connections extending along a side and transversely of one end of the motor.

2. A pump comprising, in combination, a low compact base frame providing parallel vertical 5 pump chambers and having a bottom wall which provides the bottoms for said chambers and on which the pump is adapted to be supported, said chambers opening upwardly through the top of the base frame, diaphragms providing flexible 10 top walls for said pump chambers, a pedestal frame mounted on the top of said base frame between said pump chambers and projecting upwardly from the top of said base frame, said pedestal frame providing a gear housing, a motor 15 supported by said pedestal frame and overhanging said base frame with its bottom surface disposed above the bottom of said base frame, gearing in said gear housing and driven by said motor, means arranged exteriorly of said pedestal 20 frame and driven by said gearing for flexing said diaphragms to effect intake of fluid into and discharge of fluid from said pump chambers, and supply and discharge passage means for said 25 chambers and arranged above the bottom of said base frame.

3. A pump comprising, in combination, a base frame providing parallel vertical pump chambers and having a closed bottom wall which provides the bottoms for said chambers and on which the 30 pump is adapted to be supported, said chambers opening upwardly through the top of the base frame, diaphragms providing flexible top walls for said pump chambers, a pedestal frame mounted on the top of said base frame between said 35 pump chambers and projecting upwardly from the top of said base frame, said pedestal frame providing a gear housing, a motor supported by said pedestal frame and overhanging said base frame with its bottom surface disposed above 40 the bottom of said base frame, gearing in said gear housing and driven by said motor, a horizontal shaft journaled on said pedestal frame and extending transversely over the top of said base frame, said shaft driven by said gearing, 45 means arranged exteriorly of said pedestal frame and driven by said transverse shaft for flexing said diaphragms to effect intake of fluid into and discharge of fluid from said pump chambers, and supply and discharge passage means for said 50 chambers and arranged above the bottom of said base frame.

4. A pump comprising, in combination, a base frame providing parallel vertical pump chambers and having a closed bottom wall which provides the bottoms for said chambers and on which the 55 pump is adapted to be supported, said chambers opening upwardly through the top of the base frame, diaphragms providing flexible top walls for said pump chambers, a pedestal frame mounted on the top of said base frame between said 60 pump chambers and projecting upwardly from the top of said base frame, said pedestal frame providing a gear housing, a motor supported by said pedestal frame and overhanging said base 65 frame with its bottom surface disposed above the bottom of said base frame, gearing in said gear housing and driven by said motor, a horizontal shaft journaled on said pedestal frame and extending transversely over the top of said base 70 frame, said shaft driven by said gearing, means arranged exteriorly of said pedestal frame and driven by said transverse shaft for flexing said diaphragms to effect intake of fluid into and discharge of fluid from said pump chambers, said 75

last mentioned means comprising crank pins formed on the projecting ends of said shaft and plunger-like members actuated by said crank pins and connected to said diaphragms, said 5 plunger-like members arranged at the opposite sides of said pedestal frame, and supply and discharge passage means for said chambers and arranged above the bottom of said base frame.

5. A pump comprising, in combination, a base 10 frame providing parallel vertical pump chambers and having a closed bottom wall which provides the bottoms for said chambers and on which the pump is adapted to be supported, said chambers opening through the top of the base frame, said 15 frame having vertical webs extending across said chambers below the tops thereof for reinforcing said base frame, said webs formed with flow passages, diaphragms providing flexible top walls for said pump chambers, a gear housing supported on said base frame and containing intermeshing 20 gearing, a motor for driving said gearing and arranged above the bottom of said base frame, intake and discharge passage means communicating with said chambers and arranged above the 25 bottom of said base frame, and means driven by said gearing for flexing said diaphragms to effect intake of fluid into and discharge of fluid from said pump chambers.

6. A pump comprising, in combination, a base 30 on the bottom of which the pump is adapted to be supported and having pump chambers formed therein, a motor supported by said base with its bottom disposed above the bottom of said base and having its power shaft horizontally disposed 35 in horizontal planes above said pump chambers, flexible diaphragms in said chambers for creating a suction in said chambers and for forcing fluid from said chambers, driving connections between said motor power shaft and said diaphragms for flexing the latter, and inlet and discharge connections extending along the sides and transversely of said base in common horizontal planes above the bottom of said base and near the bottom of said motor, said connections 40 communicating with said pump chambers, and certain of said pipe connections extending along the sides and across one end of said motor.

7. A pump comprising, in combination, a low compact base frame providing parallel vertical pump chambers and having a bottom wall which provides the bottoms for said chambers and on which the pump is adapted to be supported, said 5 chambers opening upwardly through the top of the base frame, diaphragms providing flexible top walls for said pump chambers, a pedestal frame mounted on top of said base frame between said pump chambers and projecting upwardly 10 from the top of said base frame, said pedestal frame providing a gear housing, a motor supported solely by said pedestal frame in overhanging relation to said base frame, the bottom surface of said motor disposed above the bottom of said base frame, gearing in said gear housing and driven by said motor, means arranged exteriorly 15 of said pedestal frame and driven by said gearing for flexing said diaphragms to effect intake of fluid into and discharge of fluid from said pump 20 chambers, and supply and discharge passage means for said chambers and arranged above the bottom of said base frame.

8. A pump comprising, in combination, a base 25 frame providing parallel vertical pump chambers and having a closed bottom wall which provides the bottoms for said chambers and on which the pump is adapted to be supported, the chamber bottoms spaced by a recess, said frame having vertical webs extending across said chambers 30 below the tops thereof and across said recess for reinforcing said base frame, said vertical webs extending across said chambers formed with flow passages, diaphragms providing flexible top walls for said pump chambers, a gear housing 35 supported on said base frame and containing intermeshing gearing, a motor for driving said gearing and arranged above the bottom of said base frame, intake and discharge passage means communicating with said chambers and arranged 40 above the bottom of said base frame, and means driven by said gearing for flexing said diaphragms to effect intake of fluid into and discharge of fluid from said pump chambers.

JOSEPH F. JOY. 45
